UNITED STATES PATENT OFFICE.

THOMAS H. DEVEAUX, OF TOLEDO, OHIO.

DESIGN FOR A TAG.

SPECIFICATION forming part of Design No. 25,274, dated March 24, 1896.

Application filed November 25, 1895. Serial No. 570,119. Term of patent 7 years.

To all whom it may concern:

Be it known that I, THOMAS H. DEVEAUX, of Toledo, county of Lucas, and State of Ohio, have invented and produced a new and original Design for Price-Tags; and I do hereby declare that the following is a full, clear, and exact description of the invention, which will enable others skilled in the art to which it appertains to make and use the same, reference being had to the accompanying drawing, and to the figures of reference marked thereon, which form part of this specification.

The figure illustrated in the drawing is a perspective view of the tag, showing the design of the same.

The leading feature of my design consists in the body of the tag, substantially circular, with a portion of the same extending beyond the diameter of the body, said portion being in the same horizontal plane and having two depending arms extending in parallel relation to each other.

1 designates the body, circular in shape, as shown, a portion 2 extending at one side of the same beyond the diameter of the body, 25 said portion 2 being in the same horizontal plane as the body, depending from the body at the joinder of the same, and the portion 2 is an arm 3, there being a like depending arm 4 extending from the outer end of the portion 2, the arms 3 and 4 being parallel to each other.

What I claim is—

The design for a tag substantially as herein set forth.

In testimony that I claim the foregoing as my own I hereby affix my signature in presence of two witnesses.

THOMAS H. DEVEAUX.

Witnesses:

PETER J. MEULER,
WILLIAM WEBSTER.
